DESIGN

Design No. 2,848

OF A

WINDOW FASTENING

United States Patent Office.

GEORGE BYRON KIRKHAM, OF NEW YORK, N. Y.

Design No. 2,848, dated December 17, 1867.

DESIGN FOR A WINDOW-FASTENER.

The Schedule referred to in these Letters Patent and making part of the same.

TO ALL WHOM IT MAY CONCERN:

Be it known that I, GEORGE BYRON KIRKHAM, of 167 East Thirty-Third street, of the city of New York, in the county of New York, and State of New York, have originated and designed a new Ornamental Window-Fastening, of which the following is a full, clear, and exact description, reference being had to the accompanying drawings, which form a part of this specification, and in which—

Figure 1 represents an end and side of the fastening in perspective.

Figure 2 shows a front view; and

Figure 3 shows one side.

This fastening consists essentially of a wedge-shaped piece of metal, having an ornamental leaf and tendril worked on the front of it, at one end a representation of a fruit or ball, to serve for a knob to take hold of, and on the face of the wedge several ridges or sharp edges, to engage with and hold the sash, while between these ridges are the letters perfect, that being the motto or descriptive name which I propose to use with it.

To put it in working order, a mortise must be cut in the side of the window-casing to admit the fastening, and when it is in, a nail or screw is driven under it, the head of the nail sliding freely along the depressed part of the face A A, but catching against the prominence B B, and thus preventing the fastening from coming entirely out. At C there is a depression, which allows the nail to catch in the fastening, and hold it when it is pushed in far enough.

What I claim as my invention, and desire to secure by Letters Patent, is—

The design for a window-fastening, as represented and herein set forth.

GEO. B. KIRKHAM.
